UNITED STATES PATENT OFFICE.

CHARLES VOLNEY KERR, OF WELLSVILLE, NEW YORK.

CONDENSER.

1,159,775.

Specification of Letters Patent.

Patented Nov. 9, 1915.

Application filed October 23, 1913. Serial No. 796,747.

To all whom it may concern:

Be it known that I, CHARLES V. KERR, a citizen of the United States, residing at Wellsville, in the county of Allegany and 5 State of New York, have invented certain new and useful Improvements in Condensers, of which the following is a specification.

My invention relates to condensers of the surface type and is particularly adapted to 10 be used in connection with steam turbine plants.

The objects of my invention are, first, to construct and arrange the parts of the condenser so that the steam is evenly distributed 15 throughout the vertical steam tubes with the least resistance to its flow thereby decreasing the back pressure and materially increasing the vacuum produced in the condensing chamber; second, to arrange the tubes carrying 20 the exhaust steam with respect to the inlet and outlet of the water of the condenser so that short tubes may be employed and each tube acts independent of any other tube; third, to arrange the condensing tubes 25 in such a manner with respect to the inlet and outlet of the exhaust steam and their relation with the inlet and outlet of the water, so that the steam with a minimum resistance sweeps both the condensed steam 30 and entrained air ahead of it in each tube, into the hot-well situated below the tubes; fourth, to construct and arrange the parts of 35 the condenser, so that the tubes may be of minimum length without destroying the efficiency and capacity of the condenser; fifth, to construct and arrange the elements of the condenser so that the adoption of short vertical tubes, enables the use of thin tube sheets into which the ends of each tube are 40 readily expanded thus avoiding the cost and labor, and repair of two stuffing boxes for each tube used; sixth, to construct and arrange the tube sheets with respect to the casting of the condenser so that the tube sheets 45 with the ends of the tubes secured thereto are capable of "breathing" with the expansion of the attached tubes; seventh, to construct and arrange the parts of the condenser so that any air which may have a 50 tendency to collect in the upper section of the water chamber of the condenser will be quickly removed by the discharge of the water; eighth, to arrange the tubes with relation to the tube sheets, water inlet and out-

let, and hot-well, so that any leakage at the 55 joints of the tubes and sheets may be readily detected by the flow of water into or discharge from the hot-well; ninth, to so construct and arrange the parts as to make a condenser which is compact, of low first cost, 60 of a high and constant efficiency, and in which all the parts are easily assembled or taken apart, quickly inspected or repaired, and kept clean of incrustation; tenth, other objects and advantages of construction will 65 appear from the detailed description to be hereinafter given in connection with the preferred form, shown in the drawings.

My invention consists of structural features and relative arrangements of the elements comprising the invention, which will be hereinafter more fully described and particularly pointed out in the appended claims.

In the drawings in which similar reference characters indicate the same parts in 75 the several figures: Figure 1 is a longitudinal central section of the condenser on line I—I of Fig. 2; Fig. 2 is a transverse sectional view on line II—II of Fig. 1 with the lower baffle plate removed; Fig. 3 is an enlarged fragmentary and sectional view of one of the condenser tubes, tube sheets and baffle plates; and Fig. 4 is an enlarged top plan view of the upper tube sheet with the tubes attached.

Referring to the drawings 1 is the condenser casing having open ends and provided with a lower cooling water inlet 2 and an upper water outlet or discharge 3. Said casing may be provided with the usual hand 90 holes 4 and 5, for the purpose of inspecting the condition, repairing or cleaning the interior of the condenser. Attached to the flanges of the top and bottom openings of the casing 1 are thin tube sheets 6 and 7, 95 through which are passed and secured a series of short brass tubes 8, 8, tinned on their inner and outer sides and arranged in a staggered relation, as shown in Fig. 2.

The tubes 8, 8, are preferably secured to 100 the sheets 6 and 7, by expanding the ends of the tubes adjacent the sheets, thereby avoiding the expense of providing stuffing boxes or other packing means at each end. The upper ends of the tubes 8, 8, are also 105 beaded to reduce the resistance and make the entrance of the steam easier into said tubes.

9, 9, are baffle plates preferably of the same material as the tubes 8, 8, and tube sheets 6 and 7, and drilled with holes larger than the tubes, for the purpose of not only permitting any sediment to easily pass down and off of the plates through the clearance between the tubes and plates to the bottom of the casing 1, but at the same time allow the tubes to expand longitudinally. Said plates 10 9, 9, may be held and supported in the position shown in the casing 1 and between the sheets 6 and 7, by any suitable means, and thereby cause the water to make three passes across the tubes 8, 8, before passing out 15 through the discharge 3, and as the tubes are vertical and the water has an eddying flow across them, said tubes are constantly cleaned of all matter having a tendency to adhere to them. It will also be readily seen 20 that owing to the large section of the condenser shell or casing 1, the velocity of the water across and through the condenser is low, about two feet per second, and the water is constantly being mixed up by the 25 staggered relation of the tubes, whereby a uniform rise of temperature is secured with the most effective maximum cooling effect produced from the water used.

Attached to the upper end and over the 30 opening of the casing 1 is a cap 10 having an exhaust inlet or opening 11. Secured to the bottom of and supporting the casing 1 and arranged below the outlet of the tubes 8, 8, is a hot-well 12, which is provided with 35 an upper annular air receiving chamber 13 below the lower ends of the tubes 8, 8, said chamber 13, having an opening 14 connected with any suitable form of vacuum pump or preferably with a barometric pump, as 40 shown for example in my co-pending application filed Oct. 29, 1913, Serial Number 797,960. At the bottom of the hot-well is an opening 15 for the discharge of the condensed steam which is connected to any suitable type of centrifugal or piston pump for 45 feeding steam boilers.

16, 16 are supports for the condenser which engage the underside of a flange formed on the hot-well casing 12 by the annular chamber 13.

To provide for the expansion and contraction of the tubes 8, 8, which have their ends expanded into the holes of and rigidly connected with the tube sheets 6 and 7, and 55 to permit each of the said tube sheets to "breathe" or slightly rise and fall, due to said expansion and contraction of the tube, I have slightly cut away at 17, as shown, the inner edges of the meeting flanges of the top 60 and bottom of the casing 1, bottom of the cap 10 and top of the hot-well 12, whereby is formed the V-shape annular clearance of space which permits the outer section of said sheets to have a slight movement up or 65 down from the horizontal and thereby re-

lieve said tube sheets 6 and 7 and tube connections, of any distorting strains, which would have a tendency to start the joints between the sheets and tubes to leak, and permit the cooling water to enter into the 70 tubes 8, 8, and destroy the efficiency of the condenser.

The operation of the invention is as follows: Water from the circulating pump being admitted into the lower water inlet 2, it 75 passes at first in contact with and around the lower section of the tubes 8, 8, and owing to the staggered relation of the tubes is thoroughly mixed and agitated to insure a uniform cooling effect. The water, due to the 80 arrangement of the baffle plates 9, 9, takes a sinuous course upwardly and makes in the present form, as shown, three passes across the tubes 8, 8, before said water passes out through the upper discharge opening 3. 85 Any air which may collect at the upper section of the water chamber or casing 1, and below the plate 6, is entrained by the heated discharging water, and carried out of the outlet 3 to the pump, not shown. The steam 90 entering at the top through inlet 11 passes into the top of the tubes 8, 8, and is condensed into a thin film of moisture therein by the cooling water surrounding the outside of said tubes, and as said steam is condensed on the inside of the tubes 8, 8, the 95 incoming steam sweeps both the condensed steam or film of water, and the air, ahead of it to the lower ends of each of the tubes from which said water and air are discharged into 100 the hot-well 12 below the tubes, said air collecting in the chamber 13, and the water passing out through the opening 15 to a feed pump, not shown. The air collecting at the 105 top of the hot-well 12 in the chamber 13 is continuously drawn out through the opening 14 by an air pump, not shown.

From the foregoing arrangement it will be seen that each condensing tube acts independent of any other, and the condensed 110 steam with the air liberated therefrom are brought in contact with and stored in proximity to the coolest water in the condenser, which assures and makes it practicable to maintain a vacuum approaching that due to 115 the cooling water temperature. Discharging the water at the top brings the warmest water in contact with the section of the tubes first receiving the incoming steam and this water is in the best position for entraining the air which may collect on the upper sections of the tubes 8, 8, and water space or casing 1 and under the upper tube sheet 6.

As will be seen from the foregoing description of the operation of the apparatus, 125 all the objects recited in the statement of invention are fully and efficiently carried out and a compact condenser is produced which is capable not only of condensing the maximum amount of steam with a minimum 130

use of water, but at the same time approaching nearer the vacuum due to temperature of cooling water used.

What I claim is:—

1. A surface condenser comprising a casing having an inlet for steam in the top thereof, vertical steam tubes arranged within the casing, a lower inlet and an upper outlet for the cooling water in the casing, baffle plates within the casing for directing the flow of cooling water back and forth across or substantially at right angles to the steam tubes, a hot well at the bottom of the casing communicating with the tubes and having an outlet for condensed steam at the bottom, and an air chamber at the upper end adjacent to the lower end of the tubes, and an air pump connection in the hot well adjacent to and below the steam tubes.
2. A surface condenser comprising a casing having upper and lower open ends and provided with a lower water inlet and an

upper water outlet, tube sheets closing the upper and lower open ends, separated baffle plates between the tube sheets extending partly across the casing alternately from opposite sides, vertical steam tubes passing through the tube sheets and baffle plates and connected with the tube sheets, a cap having a steam inlet attached to the upper end of the casing and communicating with the steam tubes, and a hot well having an upper annular air chamber, and a discharge opening adjacent to the lower end of the tubes, said hot well also having a condensed steam outlet at its lower end and being secured to the lower end of the casing and communicating with the steam tubes.

In testimony whereof I affix my signature in presence of two witnesses.
